1. A tie holder and press comprising a cover which is situated to receive a number of ties to be bent over a central crease prior to being folded and otherwise holding said ties in a relatively loose and free form to permit the removal of wrinkles and creases from the same and a plurality of leaves C of flexible material which are attached to the cover and which are arranged to support the ties in a flatwise position and to hold them in a relatively loose form, the leaves being attached to the cover by means of a series of snap fasteners.

COMBINED TIE PRESS AND HOLDER

Harrison O. Joseph, Los Angeles, Calif.

Application August 4, 1944, Serial No. 548,070

2 Claims. (Cl. 38-72)

This invention relates to and has for an object, the provision of a combined tie holder and press, by means of which a plurality of ties may be supported in flatwise positions in a common holder which, when closed, will serve to remove wrinkles and creases from ties not in use, and will afford ready access for the removal of ties therefrom.

This invention comprehends the provision of a combined tie holder and press which, in its broadest aspect, includes an accordion-like body, preferably, but not necessarily, formed of a single piece of reasonably stiff, durable material and with a series of flat sections of uniform size which are alternately extended in oppositely inclined directions and between which tie holding leaves are arranged and so formed as to support ties against lateral removal therefrom.

An object, also, is to provide a tie holder and press of the character mentioned which includes a sheet, or sheets, of material attached to the body at a requisite number of points for limiting the expansion of the body as when the holder is opened for the insertion or removal of ties therefrom.

A further object is to provide suitable means for securing the extremities of the body together when the body is contracted, so as to compress the contents of the holder.

Another object is to provide a suitable cover for the body and its contained ties which serves to enclose the body and ties when it is closed and yet affords access for the removal of a desired tie without being opened. Other objects may appear as the description progresses.

I have shown a preferred form of structure embodying my improvements in the accompanying drawing, subject, however, to modification within the scope of the appended claims, without departing from the spirit of the invention. In said drawing:

Fig. 1 is a perspective view of a combined tie press and holder embodying my improvements and shown in collapsed and closed position;

Fig. 2 is a perspective view of the same partly open;

Fig. 3 is an end view of the same inverted from the position shown in Fig. 1;

Fig. 4 is a fragmentary perspective view of the same shown in section on an enlarged scale; and

Fig. 5 is an end view with the body and leaves extended as for the purpose of placing ties therein.

Briefly described, a combined press and holder

is shown which is a laboratory retort holder and tie holder.

Fig. 1 shows the holder in a closed position.

Fig. 2 shows the holder in an open position.

same end of the holder for removal at will without actually opening the holder.

It may be noted that the bottom D is formed with the pleats 12-13 thereof which are substantially narrower than the corresponding portions b, b, of the body B. Thus, when the holder is fully extended and portions 12 and 13 of the bottom are in the same horizontal plane, the portions b, b, of the body will still be disposed at substantial angles relative to each other, and the leaves C will at such time be substantially vertical, as shown in Fig. 5. When removing or inserting a tie it is not always necessary to completely open the holder, at least to the extent shown in Fig. 5, inasmuch as it will be apparent that when the cover A is unfastened and partially extended, it is necessary only to expand that portion of the body between adjacent pleats sufficiently to remove one tie and replace it with another, after which the cover is again closed and fastened and all of the ties therein will be simultaneously pressed for further use.

What I claim is:

1. A combined tie press and holder comprising: a foldable cover, a first accordion-like member formed of leaves alternately hinged at opposite margins, the initial leaf being secured to a section of the cover, intermediate leaves foldably secured to and between adjacent leaves of said first member for supporting ties, and a second accordion-like member also having leaves foldably connected to the leaves of said first member at corresponding junctional points, for limiting the extension of the leaves of said first member when the holder is opened, the leaves of said second member being of lesser width than and adapted to nest between adjacent leaves of said first member when the holder is closed.

2. A combined tie press and holder comprising: a foldable cover, a first accordion-like member formed of leaves alternately hinged at opposite margins, the initial leaf being secured to a section of the cover, intermediate leaves foldably secured to and between adjacent leaves of said first member for supporting ties, and a second accordion-like member also having leaves foldably connected to the leaves of said first member at corresponding junctional points, for limiting the extension of the leaves of said first member when the holder is opened, the leaves of said second member being of lesser width than and adapted to nest between adjacent leaves of said first member when the holder is closed, the difference in width between the leaves of the first and second members being such as to permit the extension of the first member horizontally when the cover is disposed flatwise on a surface so as to afford access to all of the ties carried by the intermediate leaves.

HARRISON O. JOSEPH.
